Attorney

UNITED STATES PATENT OFFICE.

BRUNSON S. McCUTCHEON, OF PLAINFIELD, NEW JERSEY.

WASHING MACHINE.

Application filed October 5, 1920. Serial No. 414,884.

To all whom it may concern:

Be it known that I, BRUNSON S. McCUTCHEON, a citizen of the United States of America, residing at Plainfield, in the county of Union and State of New Jersey, have invented certain new and useful Improvements in Washing Machines, of which the following is a specification.

My invention relates to improvements in washing machines and has for its object to provide a quick detachable power unit which when connected to the washer serves to operate the washing and wringing mechanism of the washing machine and which when disconnected serves as a vacuum cleaner.

Other and further objects and advantages of my invention will be in part described and in part obvious as the specification is proceeded with.

20 In the accompanying drawings forming part of this specification:

Figure 1 is a side view of a washing machine with power unit attached;

Figure 2 is a detail view of the detachable coupling between the main shaft of the washing machine and the drive shaft of the power unit; and

Figure 3 is a detached view of one of the pivoted arms for securing the power unit carriage to the washing machine frame.

Referring more particularly to the drawings wherein is illustrated a preferred embodiment of my invention, the numeral 1 designates any preferred form of rotary washing machine comprising a frame 5, having a clothes container casing 6 therein. The gearing and shafting for actuating the clothes container (not shown) and for rotating the rolls of the wringer 7, generally indicated by the numeral 8, is suitably connected to and driven from the main shaft 9 of the washing machine.

My portable power unit comprises a wheeled base or carriage 10, mounted upon which is a motor 11 and a blower or pump 12 of any approved design, the latter being connected to a vacuum cleaner nozzle 22 by means of a hose or the like 23.

Any suitable means such as clutch 24 is provided for disconnecting the pump or

blower from the motor when the motor is being used to drive the washing machine, but this is not absolutely necessary as the opening of relief valve 25 will relieve the blower load.

The drive shaft 13 of the motor is formed at one end with a flexible disk 14 formed with a plurality of spaced openings 15 adapted to receive correspondingly spaced pins 16 projecting from the outer face of a preferably steel disk 17 in turn carried by the shaft 9. Connection can be quickly made by the operator wheeling the portable power unit into position to aline the shafts 9 and 13 and then rotating the shaft 13 until the openings 15 are in proper position to receive the pins 16. When connection of the shafts has been effected the portable power unit is securely fastened to the frame 5 by means of the arms 18 (only one of which is shown) pivotally connected as at 26 to the frame, one at each side thereof.

As clearly shown in the drawings, these arms are formed on their bottom faces with recessed lugs 19 adapted to fit over the ends 75 of the axles 20 of the wheels 21, said ends being slightly extended for this purpose.

When it is desired to use the portable power unit as a vacuum cleaner the operator disconnects the shaft 13 from the shaft 9, of course first swinging the arms 18 to dotted line position.

From the foregoing it will be seen that I have provided a readily attachable and detachable power unit which is adapted to 85 serve the double function of a vacuum cleaner and power drive for washing machines.

Having thus described my invention.

What I claim is:

In a device of the character described, a frame, a main drive shaft mounted in said frame, a portable power unit for driving said shaft comprising a wheeled carriage, the wheels of said carriage having extended axles, and pivoted arms on said frame 95 adapted to swing down over and engage said extended axle ends to lock said power unit to said frame.

In testimony whereof I affix my signature.

BRUNSON S. McCUTCHEON.
